J. SOSS.

WINDOW FRAME FOR AUTOMOBILE HOODS.

APPLICATION FILED JAN. 30, 1919.

1,364,459.

Patented Jan. 4, 1921.

FIG. 1.

FIG. 3. FIG. 4.

FIG. 5. FIG. 6.

FIG. 7.

Inventor
Joseph Soss,
By his Attorneys
Edgar V. Atchley

UNITED STATES PATENT OFFICE.

JOSEPH SOSS, OF NEW YORK, N. Y.

WINDOW-FRAME FOR AUTOMOBILE-HOODS.

1,364,459.

Specification of Letters Patent.

Patented Jan. 4, 1921.

Application filed January 30, 1919. Serial No. 273,933.

To all whom it may concern:

Be it known that I, JOSEPH Soss, a citizen of the United States, and residing at New York, in the county of New York and State 5 of New York, have invented certain new and useful Improvements in Window-Frames for Automobile-Hoods, of which the following is a specification, such as will enable those skilled in the art to which it 10 appertains to make and use the same.

This invention relates to frames for use in supporting window panels and particularly to devices of this class used in connection with flexible hoods of automobiles or 15 other vehicles; and the object of the invention is to provide a frame of the class specified with improved means for securing a transparent panel therein and also improved means for securing the frame in the hood of 20 the automobile or in a flexible fibrous body or sheet of any kind; and with this and other objects in view the invention consists in a device of the class specified, constructed and operating as hereinafter described and 25 claimed.

The invention is fully disclosed in the following specification, of which the accompanying drawing forms a part, in which the 30 separate parts of my improvement are designated by suitable reference characters in each of the views, and in which:—

Figure 1 is an outside view of my improved window frame and showing the same in use;

Fig. 2 a section on the line 2—2 of Fig. 1; Fig. 3 a sectional detail view of the outer part of the frame;

Fig. 4 a view similar to Fig. 2 of the inner part of the frame;

Fig. 5 a view similar to Fig. 2 but showing another form of construction;

Fig. 6 a sectional detail view of the inner part of the frame shown in Fig. 5; and,

Fig. 7 a view similar to Fig. 6 of the outer part of the frame shown in Fig. 5.

In the practice of my invention, as shown in Figs. 1 to 4 inclusive, I provide a window panel frame *a* which, as shown in the drawing, is elliptical in form but which may be 50 round or of any other desired shape. The

frame *a* is composed of an inner part *b* preferably of wood and an outer part *c*, preferably of metal, and the outer part *c* is shown in Fig. 3 while the inner part *b* is shown in Fig. 4.

The outer part *c* comprises a body portion *c*² which is plano-convex in cross section and a web portion *c*³ which projects at right angles from the plain side of the body portion and is preferably slightly tapered outwardly and is provided at intervals with holes or apertures *c*⁴.

The part *b* comprises a body portion *b*² and a top inwardly directed flange or shoulder portion *b*³ and the transverse dimensions 65 of the body portion *b*² are approximately the same as the transverse dimensions of one side portion of the body portion *c*² of the outer member *c* of the frame, as clearly shown in Fig. 2.

In the accompanying drawing I have shown at *d* a part of the hood of an automobile which may be of leather, canvas, or any other suitable flexible material or a flexible fibrous body of any kind, and in the use of the 70 window frame shown in Figs. 1 to 4 inclusive, the part *c*² of the frame or the web portion *c*³ thereof may be forced into the hood material as shown in Fig. 2, after which the part *b* of the frame is forced into position, 75 after which the hood material is cut out to form the opening *e*, after which the transparent panel *f* is placed in position, after which a flexible gasket or band *h* is placed within the frame as shown in Fig. 2 so that 80 it bears on the web *c*³ and securely holds the transparent panel *f* in position, after which nails or similar fastening devices *i* are passed through holes *h*² in the gasket or band *h* and through the holes *c*⁴ in the web portion *c*³ of 85 the frame and into the body of the part *b* of the frame as clearly shown in Fig. 2, and the transparent panel is securely bound in the frame and said frame in the body of the hood, with the said panel and hood body 90 in the same or parallel planes.

In this form of construction the top inwardly directed flange member *b*³ of the part *b* of the frame overlaps the web portion *c*³ and overlaps the edge of the hood material, 100

or the edge of the hood portion formed by cutting out the opening *e*, and also overlaps or partially overlaps the gasket or band *h* and a neat and finished appearance is given to the inner side of the frame, and the inner part *b* of the frame securely binds and holds the frame in the hood without crimping or twisting the hood material outside of the frame, and the nails *i* securely bind the 10 separate parts of the frame together and aid in securing the hood material therein.

My invention, however, is not limited to any particular method of or means for securing the frame in the hood, or the method 15 of placing the frame in the hood, the said invention as shown in Figs. 1 to 5 inclusive consisting of the frame constructed as shown and described together with the gasket or band *h* which forms a part of said frame.

In the construction shown in Figs. 5 to 7 inclusive, the part *c*² of the frame is the same in form and construction as shown in Figs. 1 to 4 inclusive, except that elongated 25 holes *c*⁵ are substituted for the holes *c*⁴ shown in Fig. 3. In this form of construction, however, the inner part *b*⁴ of the frame is made U-shaped in cross section, or the inner side thereof is provided with a groove 30 or recess *b*⁵ which extends entirely around said part and opens inwardly and is adapted to receive the web member *c*³ of the part *c*², as clearly shown in Fig. 5, while the inner side portion *b*⁷ of the part *b*⁴ is shorter than 35 the outer side portion *b*⁸ so as to form an annular space between the part *b*⁷ and the part *c*² as shown at *j* in Fig. 5 to receive the transparent panel *f*.

With this construction the parts of the 40 frame may be assembled and secured in or to the hood or hood material as shown and described with reference to the construction shown in Figs. 1 to 4 inclusive, or in any way, or by any means or process that might 45 suggest itself to the operator, and after the parts have been assembled and secured to or in the hood as shown in Fig. 5, nails *k* are passed outwardly through the inner part *b*⁷ of the inner frame member and through the 50 holes *c*⁵ in the web portion *c*³ of the outer frame member and into the outer part *b*⁸ of the inner frame member as clearly shown in Fig. 5. In the operation of assembling 55 the parts of the frame as shown in Fig. 5, the hood of the automobile may entirely overlap the web portion *c*³ of the outer frame member *c*², as clearly shown in said figure, and if desired the inner frame member *b*⁴ may be inclosed by a covering or easing *m* 60 of flexible material similar to the hood material, and in this way a highly finished appearance may be given the inner side of the frame as viewed from within the vehicle, and the frame is firmly secured in the material of the hood without marring the sur-

face of the latter or without twisting, or wrinkling or crimping it in any way.

While I have shown and described the preferred form or forms of my invention, it will be understood that the said invention 70 is not limited to the details of construction herein shown and described, and changes therein and modifications thereof may be made, within the scope of the appended claims, without departing from the spirit of 75 the invention or sacrificing its advantages.

Having fully described my invention, what I claim as new and desire to secure by Letters Patent, is:—

1. A window frame of the class described 80 for use in securing a transparent panel in a flexible body of fibrous material, said frame consisting of inner and outer parts, the outer part being provided with a plain face having a central web which projects therefrom 85 and extends entirely around said part and divides the face thereof into similar outer and inner portions, and the inner part of the frame being adapted to inclose said web and to closely fit the same and to bind the 90 body of fibrous material between itself and the said web and outer face portion of the outer part of the frame, said parts of the frame being also provided with means for securing a transparent panel on the inner 95 face portion of the outer part of the frame and in the plane of the fibrous material or a plane parallel therewith, and means for securing the parts of the frame together.

2. A window frame of the class described 100 for use in securing a transparent panel in a flexible body of fibrous material, said frame consisting of inner and outer parts, the outer part being provided with a plain face having a central web which projects therefrom 105 and divides the face thereof into similar outer and inner portions, the inner part of the frame inclosing said web and closely fitting the same and binding the body of fibrous material between itself and said 110 web and the outer face portion of the outer part of the frame, said parts of the frame being also provided with means for securing a transparent panel on the inner face portion of the outer part, and fastening devices passed transversely and outwardly 115 through said web and into the inner part of the frame for securing said parts together with the fibrous material therebetween and with the transparent panel in position.

3. A window frame of the class described comprising inner and outer parts, the outer part being plano-convex in cross section and provided on the plain face thereof with a projecting web and the inner part being 125 adapted to inclose said web and to bind a fabric body between itself and the outer part, said outer part being adapted to receive a transparent panel, a flexible strip mounted on the inner face of said web for 130

holding said transparent panel in position, and devices passed transversely and outwardly through said strip, web and the inner part of the frame for securing said parts together with the fibrous body therebetween and the transparent panel therein.

5 In testimony that I claim the foregoing

as my invention I have signed my name in presence of the subscribing witnesses this 29th day of January 1919.

JOSEPH SOSS
